8 Claims. (Cl. 250—49.5)

This invention relates to the production of beams of charged particles and, more particularly, relates to apparatus for producing and shaping beams of high energy charged particles into an impinging beam of high intensity across a sharply defined cross section.

Apparatus utilizing a beam of charged particles focussed upon a material to be worked thereby are known to the art. In such apparatus, the focussing lens has been an axially symmetrical lens. The lens aberrations and, particularly the spherical aberration of an axially symmetrical lens, makes it very difficult to focus a beam having a large focal aperture. When focussing such a beam with an axially symmetrical lens one obtains an impinging beam which has a nonuniform intensity distribution throughout the beam cross section. The intensity of the central area of this beam is greater than the intensity in the marginal zones. For this reason only the central area of the impinging beam can be used for working the material.

In order to work material by a beam of charged particles it is desirable, however, to use a beam which has a large focal aperture. Such a beam has a great intensity and allows to obtain very good working effects especially in drilling, milling or welding materials. The speed of working and the precision of control is afforded by having the intensity in the impinging beam high and by having the beam peripheral edges sharply defined by a rapid decrease of intensity.

It is, therefore, the object of this invention to provide an apparatus for producing and focussing a beam of charged particles having a large focal aperture which will have a uniformly high intensity throughout the beam cross section taken at the work piece and which will have a sharply defined peripheral edge at which the beam intensity will decrease sharply.

In accordance with this object there is provided, in accordance with a preferred embodiment of this invention, a cathode, an associated control grid and an anode for producing a beam of charged particles having a large focal aperture. Such apparatus will produce high beam energy with tolerable cathode emission current density levels. A cylindrical lens is positioned to focus the beam upon the surface of material to be worked thereby. The cylindrical lens is corrected for aberrations and has a large angular field of view which can encompass the relatively large emitting surface of the cathode of the beam producing system. The focussing of the beam energy distributed over a large angular field by an aberration-corrected cylindrical lens provides a beam impinging upon the material having a substantially rectangular plot of energy intensity across the cross section.

It is often advantageous to employ a linearly developed cathode, that is, a cathode having a dimension along one axis greater than the dimension along a co-ordinate axis. With such a cathode, it is possible to utilize a larger emitting cathode surface than is the case with round cathodes. In such embodiments it is desirable to align the direction of the linearly extending cathode with the main axis of the cylindrical lens serving to focus the beam. In such arrangement, a line focus will be formed on the material instead of the round focal point usually associated with beam working apparatus. A line focus

2

is not directly useable in certain applications as, for example, the drilling of round holes in the material to be worked. In such applications it is desirable to employ a rotating field between the material and the lens to rotate the beam about its center of area to give a working beam of effectively circular cross section.

The cylindrical lens is preferably an electro-magnetic cylindrical lens. Such a lens has the advantage of permitting ease of variation in the length of beam focal line by merely changing the coil current. Thus, when employed with a rotating field for drilling round holes in a material, the diameter of the bore can be varied by variation of field current in the magnetic lens. Thus, control over the diameter of the bore over a predetermined range is afforded.

In those applications where it is desired to employ the focussed beam for the purpose of producing profiled borings or milling of the material surface, the use of a cylindrical lens in combination with a rotating magnetic field requires relatively complex beam control apparatus. In such cases it is desirable to use two or more cylindrical lenses spaced apart along the axis of the beam. The axis of the cylindrical lenses are arranged at right angles, one to the other. Such arrangement will allow production of a beam of more suitable cross sectional shape.

Thus, it is seen that by the use of cylindrical lenses, focussing of the beam with very high accelerating voltages and a large cathode focal aperture can be controlled with comparatively small magneto-motive force in the individual lenses. The cylindrical lenses are more easily corrected for aberrations. Thus, high beam intensities in a sharply defined beam are obtainable in manner feasible with available materials.

This invention may be more easily understood by a reference to the specification and to the accompanying drawing of which:

FIGURE 1 is a diagrammatic view of one embodiment of the apparatus in accordance with this invention;

FIGURE 2 is a top view of a doublet cylindrical lens;

FIGURE 3 is a cross sectional view of the impinging beam of charged particles;

FIGURE 3a is a curve of the intensity distribution along the X axis of FIGURE 3 with intensity plotted along the axis of ordinates against distance plotted along the axis of abscissa;

FIGURE 3b shows the intensity distribution along the Y axis of FIGURE 3 with intensity plotted along the axis of ordinates against distance plotted along the axis of abscissa;

FIGURE 4 is a cross sectional view of the beam of charged particles produced by two cylindrical lenses arranged with the primary axis perpendicular one to the other;

FIGURE 5 is a top view of a 4-fold cylindrical lens.

In the apparatus for producing and shaping a high intensity beam of charged particles for working material, shown in FIGURE 1, the beam is produced by a system composed of a cathode 1, a control grid 2 and an anode 3. The cathode may be made of any conventional material but is preferably a linearly developed cathode, that is, its extension perpendicular to the plane of the drawing is greater than its extension in the plane of the drawing.

The cylindrical lenses 4 and 5 for focussing the beam are arranged between the anode 3 and the workpiece material 7 upon which the beam is to be focussed. A lens 6 is provided to generate a rotating field to rotate the beam. The beam of charged particles 8 is focussed by the cylindrical lenses 4 and 5 to have its smallest cross sectional area in the plane of the working piece 7.

The cylindrical lenses 4 and 5 are corrected with a respect to aberration by appropriate shaping of the pole shoes and/or by mounting specially shaped ferromagnetic members which influence the distribution of the magnetic field in the air gap between the poles. Such corrective steps are known to the art.

As can be seen more clearly from FIGURE 2, each of the cylindrical lenses is comprised of 4-pole pieces 9, 18, 16 and 17 each of which is developed as an equilateral hyperbole surrounded respectively by electromagnetic coils 10, 15, 13 and 14. The magnetic field closes through the central aperture of the lens (through which the beam of charged particles passes) and through the ferromagnetic ring 11 joining the poles. The entire lens is contained within a container 12 of nonmagnetic material. It has been found advisable to embed the pole pieces and the coil of the lens in a potting compound 19 such as synthetic resin to prevent displacement of the pole pieces from their desired position during operation.

The cylindrical lenses are developed with the coils thereof lying in a plane perpendicular to the axis of a beam of charged particles. Thus, an extremely thin construction is obtained which is advantageous in correcting the lens for aberrations and which ensures that the lens occupies very little space in the vertical direction.

It is possible to use electro-static cylindrical lenses instead of the electro magnetic cylindrical lenses shown in the drawing. However, the use of electrostatic lenses makes it necessary to apply very high voltages to the electrodes in order to focus particles of high velocity.

The beam focussed by only one cylindrical lens upon the surface of the material to be worked is shown in FIGURE 3. As is characteristic of a cylindrical lens, the cross section 20 of the focus beam will extend along a line. However, the intensity distribution within the cross sectional area, illustrated by curve 21 in FIGURE 3a and curve 22 in FIGURE 3b for the X and Y coordinates respectively is almost rectangular in shape. Thus the high intensity is substantially constant across the beam and the beam peripheral edges are defined by a sharp drop in intensity.

In some applications, such as the drilling of round holes into a work piece, the elliptical outline of the beam focussed upon the surface makes it difficult to suitably control drilling by such beam. In such applications it is advantageous to employ a rotating field generated by lens 6 to rotate the focussed beam about its center of area. Rotation of the beam will produce a working beam having an effective cross section which is round, illustrated by broken line 25 in FIGURE 3. Variation of the diameter thereof within predetermined limits can be effected conveniently by adjustment of the coil current in the cylindrical lens.

In some applications control of the rotating field in combination with the control of the cylindrical lens is complicated. In such applications it is often preferable to employ two cylindrical lenses 4 and 5 as shown in FIGURE 1. The major axis of cylindrical lens 5 is perpendicular to the axis of lens 4. Thus, the beam will be focussed successively by the two cylindrical lenses to give a cross section 23, FIGURE 4, of clover leaf outline. It will be noted that additional cylindrical lenses may be employed to shape the beam to more nearly circular cross sectional shape. In such applications it is possible to dispense with the rotating field lens during working of the material including the drilling of round holes in the material.

It will be noted that the cylindrical lenses 4 and 5 may be combined into a single compound lens as is shown in FIGURE 5. In FIGURE 5 the lens 24 comprises 8 poles with eight associated electromagnetic coils. Each of the pole pieces is developed as an equilateral hyperbole and the remaining structure is the same as set forth in

the explanation of the cylindrical lens shown in FIGURE 2.

Thus, the apparatus in accordance with this invention allows the focussing of a high intensity beam of charged particles having a sharply defined cross sectional outline. The energy is derived from a charge particle emission system having a large focal aperture.

In welding materials by means of a beam of charged particles a very high intensity of the impinging beam is necessary. Therefore, it is especially advantageous to employ the apparatus according to the invention for such welding. This apparatus may further be employed advantageously for drilling, milling, surface treating and hardening or other working of material by a beam of charged particles.

It will be noted that for some of these working effects the beam may be controlled by pulses during working of the material in manner known to the art without deleteriously affecting the focussing thereof.

It will be understood that this invention may be variously embodied and modified within the scope of the subjoined claims.

I claim:

1. Apparatus for producing and shaping a high intensity beam of charged particles for working material comprising a beam producing system consisting of a cathode, a control grid, and an anode, said beam producing system generating a beam of charged particles of large focal aperture, and an electromagnetic cylindrical lens positioned between said anode and said material to focus said beam on said material in an impinging beam of high intensity with a sharply defined periphery at which the beam intensity decreases sharply, said cylindrical lens being corrected for aberrations.

2. The combination in accordance with claim 1 in which the beam producing system comprises a linearly extending cathode aligned with the main axis of the cylindrical lens.

3. A combination in accordance with claim 1 which includes a second cylindrical lens positioned adjacent said first lens with the main axis thereof perpendicular to the main axis of the first cylindrical lens.

4. A combination in accordance with claim 1 which includes a lens system comprising four pole pieces symmetrically spaced about an aperture through which the beam is directed.

5. A combination in accordance with claim 1 which includes a lens system comprising eight pole pieces symmetrically spaced about an aperture through which the beam is directed.

6. A combination in accordance with claim 1 which includes means for producing a rotating magnetic field across the axis of said beam and perpendicular thereto to rotate said beam about its axis.

7. A combination in accordance with claim 4 in which said pole pieces are surrounded by coils for establishing a magnetic field and in which said coils are positioned in a plane perpendicular to the axis of the beam of charged particles.

8. A combination in accordance with claim 7 in which said pole pieces and coils of said lens are embedded in synthetic resin poured over them.
